UNITED STATES PATENT OFFICE.

CHARLES J. WENSLEY, OF HUNTINGTON, NEW YORK.

LIFE-SAVING DEVICE.

1,025,497.

Specification of Letters Patent.

Patented May 7, 1912.

Application filed August 22, 1911. Serial No. 645,383.

To all whom it may concern:

Be it known that I, CHARLES J. WENSLEY, a citizen of the United States, residing at Huntington, in the county of Suffolk and 5 State of New York, have invented certain new and useful Improvements in Life-Saving Devices, of which the following is a specification, reference being had therein to the accompanying drawing.

10 This invention relates to life saving devices, and the principal object of the same is to provide a receptacle having a rope and float held therein so that the swimmer may carry the rope and float about with him, and 15 if in danger of drowning may throw the float and rope in the direction from whence help may come so that he may be more readily rescued. It often happens that a swimmer gets under the water, and it is very difficult 20 to find him as the currents are liable to carry a helpless person in any direction. It therefore often happens that persons who have gotten under water are not found until too late to restore them to life.

25 When using this invention the person who is drowning draws the float from the receptacle and throws it in the direction from which help is expected. If the swimmer gets under water before the persons endeavoring to rescue him can reach him the 30 float remains on the surface and by picking up the float the rescuing party can easily draw in the rope thus drawing the drowning person from the water. It will thus be 35 evident that the drowning person will be rescued a great deal sooner than would be the result if it were necessary to dive under the water and look for the person.

When constructing a rescuing device 40 forming the subject-matter of this application, it will, of course, be obvious that minor changes may be made in details of construction and design, one preferred and practical form being shown in the accompanying 45 drawings wherein—

Figure 1 is a view showing the device in use. Fig. 2 is a side elevation of the device. Fig. 3 is a vertical section through the device. Fig. 4 is a vertical section taken at 50 right angles to the section of Fig. 3. Fig. 5 is a top plan view of the invention with the float removed. Fig. 6 is a perspective view of the upper portion of the receptacle.

55 Referring to the accompanying drawings by numerals it will be seen that the receptacle comprises a fabric body portion 10

which is secured to a metallic upper portion 11 held thereto by means of the binding 12 which incloses the upper portion of the fabric body portion. Belt loops 13 and 14 are 60 connected with the metallic frame 11 so that a belt 15 which passes around the swimmer's waist may be rigidly connected with the receptacle. A loop 16 is connected with the band 12 so that a rope 17 may be connected with the receptacle. The rope is normally placed within the receptacle as shown in Fig. 3, and has its inner end connected with a screw-eye 18 which is fastened in the inner end of the block 19. The block may 65 be formed of any suitable material, such for instance as cork or wood, which will float. The float acts as a closure for the receptacle thus holding the rope within the receptacle. A ring 20 is connected with a screw-eye 21 70 which is mounted in the upper portion of the float so that the float may be conveniently removed from the receptacle when necessary and also so that the float may be readily picked up.

80 In using this invention, the receptacle is connected with the belt 15 which surrounds the waist and is carried while in swimming. If the swimmer is taken with a cramp or does not have sufficient strength to reach the 85 shore, the swimmer calls for help and after withdrawing the float and rope from the receptacle, throws the float in the direction from whence help is expected. The persons endeavoring to rescue the swimmer go in 90 the direction of the float and after reaching the same pick it from the water and then draw the swimmer toward them. In this way the swimmer may be helped while the persons endeavoring to assist him are still 95 some distance from him. It should also be noted that if the swimmer goes under the water and does not come up again that the float may be picked up and by drawing the rope in the swimmer may be drawn to the 100 surface without it being necessary to dive into the water and search for him.

Having thus described my invention, what I claim is: —

1. A device of the character described 105 comprising a fabric body portion, a frame connected with the upper portion of said body portion, a rope connected with said frame and normally positioned within said receptacle, a float connected with said rope 110 and adapted to fit within said frame to close said body portion.

2. A device of the character described comprising a fabric body portion, a frame at the upper end of said body portion, a binding securing the upper portion of said 5 portion to said frame, a loop connected with said binding, a rope connected with said loop and a float connected with said rope.

In testimony whereof I hereunto affix my signature in presence of two witnesses.

CHARLES J. WENSLEY.

Witnesses:

JOSEPH L. LEICH,
E. G. DE NEAN.
